UNITED STATES PATENT OFFICE.

WILLIAM FULTON HUTCHINSON, OF BOUNDBROOK, NEW JERSEY, ASSIGNOR
TO THE ATLAS MATCH COMPANY, OF JERSEY CITY, NEW JERSEY.

MATCH-MACHINE.

SPECIFICATION forming part of Letters Patent No. 668,519, dated February 19, 1901.

Application filed June 18, 1900. Serial No. 20,491. (No model.)

To all whom it may concern:

Be it known that I, WILLIAM FULTON HUTCHINSON, of Boundbrook, county of Somerset, and State of New Jersey, have invented 5 certain new and useful Improvements in Match-Machines, of which the following is a full, clear, and exact description.

My invention relates to improvements in match-machines, and particularly to that class 10 of machines in which strips of veneer the thickness of a match-splint and with the width corresponding to the length of the splint are cut into splints and the splints held ready for dipping and dipped, if desired.

15 One object of my invention is to produce a machine of this character which is as simple as possible, which is adapted to cut simultaneously a large number of veneer strips, and which has a knife and comb held in parallel relation and arranged so that after a whole series of splints are severed by the knife each splint is accurately and automatically driven into a suitable sticking or carrying device.

25 Other objects of my invention are to produce a machine which has very little liability to get out of order, to arrange the parts so that they can be readily put in place or removed, if necessary, to provide against waste 30 of material, and especially to produce a feed mechanism and a guide-plate for the stock and splints whereby the stock shall be fed forward beneath the knife just the required distance for a set of splints and the descent 35 of the knife for the act of cutting shall cause the severed splints to just fill the slots of the guide-plate, so that the splints may be accurately driven to the carrier.

Still another object of my invention is to 40 construct a machine so that the knife after it has severed a series of splints will hold them in position in the guide-plate and to arrange the comb which pushes the splints to the carrier so that it shall make a full stroke 45 backward and forward while the knife is on the upper stroke, insuring the perfect sticking of the splints before they are released by the knife.

To these ends my invention consists of cer- 50 tain features of construction and combina-

tions of parts, which will be hereinafter described and claimed.

Reference is to be had to the accompanying drawings, forming a part of this specification, in which similar figures of reference refer to 55 similar parts throughout the several views.

Figure 1 is a side elevation of the machine embodying my invention. Fig. 2 is a vertical longitudinal section of the machine. Fig. 3 is a vertical cross-section on the line 3 4 of 60 Fig. 2 looking toward the front of the machine. Fig. 4 is a cross-section on the same line as Fig. 3, but looking in the opposite direction; and Fig. 5 is an enlarged detail longitudinal section showing the most important 65 part of the machine—viz., the cutting and sticking mechanism.

The machine has a suitable and substantial frame, so that the parts will be as rigid as possible, and, as illustrated, this frame 70 comprises a base 10, on which is supported the body portion 11, and the two sides are connected by transverse tie-rods 12.

In the upper part of the machine is a vertical slideway formed on each side of the 75 frame and made between the side bars 13 and the middle vertical bar 14, the side bars being adjustable in and out in a customary manner, so that they may be made to nicely fit the two vertically - reciprocating cross- 80 heads 15 and 16. The cross-head 15 is connected at the ends by pitmen 17 to the disks 19, having a crank connected with the disks, as shown at 18. The disks 19 are attached to a shaft 20, which is journaled transversely 85 in the machine-frame, and the shaft is driven by the gears 21 and 22, connecting it to the driving-shaft 23, (see Fig. 2,) and the latter is driven by a pulley 24 or other suitable driving means. The cross-head 16 is moved 90 up and down by means of the levers 25, which are pivoted to the ends of the cross-heads and are fulcrumed, as shown at 26, on the machine-frame 11, the levers 25 connecting by links with the slide-bars 28, each of which 95 is provided with an enlarged portion 29, in which is a cam-groove 30, essentially semi-circular in shape, which groove receives the pin 31 of a wheel or disk 32 on the counter-shaft 33. The shaft 33 is journaled parallel 100

with the shafts 20 and 23. It has a gear-wheel 34 meshing with and driven by the gear-wheel 22, as above referred to.

The slide-bars 28 are held in suitable keepers 35 and 36, and by reference to Fig. 1 it will be noticed that the crank connections described cause the cross-head 15 to have a regular up-and-down movement, while the cam mechanism referred to will give the cross-head 16 an irregular movement—that is, it will move it intermittently but quickly up and down.

It will be noticed that during every half-revolution of the shaft 33 the slide-bars 28 will be at rest; but when the pin 31 strikes the relatively flat part of the cam-groove 30 the slide-bars will be quickly reciprocated and the movement imparted to the cross-head 16.

As hereinafter described, the cross-head 15 carries the splint-cutting knife, while the cross-head 16 carries the ejecting-comb, and the parts are timed so that the comb will move down and up, while the cross-head 15 and its knife moves up.

The cross-head 15 carries a plain thin knife 37, which moves downward over the face of the knife-block 38 41. This knife-block is a guide also for the stock, as presently described; but I will call it a "knife-block" to avoid confusion of terms. It is arranged transversely in the machine, as shown in Fig. 4, is removably attached to the sides of the machine-frame, and is provided with a series 35 of vertical slots 39, each of a size to permit a strip of veneer to be thrust through it. The knife-block 38 has also forwardly-extending arms 38^a. These occur between the slots 39, being let into the ribs 43 of the feed-table 42, so as to form a continuation of the said ribs and at the same time to stiffen the knife-block. As a matter of convenience the knife-block is made into two parts, the upper part 41 (see Fig. 2) being slotted exactly like the lower part, and this arrangement is to facilitate the removal of the knife-block in case it should be necessary for any reason. The knife 37 slides close against the face of the knife-block, so as to shear off smoothly the 50 ends of the veneer strips which extend through the slots 39.

Particular attention is called to the relative arrangement of the knife 37 and the slotted knife-block. This seems a slight departure 55 from the common cutting arrangement, but is an important change for this reason. The most usual way of cutting veneer into splints is by having a knife strike the side of the veneer instead of the edge. When this is done, I have found from years of experiment that the cutting cannot be made absolutely smooth, except with the greatest difficulty, and, moreover, it is practically impossible to make a single knife cut off in this sidewise manner 60 a whole series of veneer strips; but by arranging the stock and knife so that the latter strikes upon the edges of the strips and cuts

from edge to edge the knife has the effect of a plane and cuts very smoothly. It will be seen, then, that this arrangement provides for 70 having one knife do all the work, whereas the other arrangement referred to necessitates a multiplicity of knives and imperfect work. Moreover, a single knife is particularly adapted to hold the splints nicely in the guide-slots 75 53, as will presently appear.

The machine has a feed-table 42 in front of the knife, which is removably attached to the machine-frame and has longitudinal parallel and vertical ribs 43, so that the veneer strips 80 may be held lengthwise between the ribs. The feeding is effected by the feed-rollers 44 at one end of the table and the feed-rollers 45 and 45^a at the opposite end. There is nothing new about this feed mechanism, and the 85 rollers are all idlers, except the roller 45^a, which has a ratchet-feed adapted to feed the strips forward step by step exactly the thickness of a match-splint at each step.

The ratchet-feed is as follows: On one end 90 of the shaft of the roller 45^a (see Fig. 5) is a ratchet-wheel 47, which is engaged and turned by a pawl 48 on the end of the lever 49, which lever is fulcrumed loosely on the aforesaid shaft and is slotted longitudinally, so that it 95 may be adjusted and its throw regulated. It is pivotally connected to a slide-plate 50, which is moved backward and forward, as presently described, and which consequently works the lever 49 and the ratchet mechanism 100 therewith connected. This is not shown or described with great particularity, for the reason that the feed can be otherwise made by the use of any of the well-known feeding devices without departing from the principle 105 of the invention. The means of operating the plate 50 and the connection of the plate there will be hereinafter described.

Just behind the knife-block 48 is a guide-plate 51, which is removably attached to the 110 machine-frame, this guide-plate being beveled off preferably at the top, as shown at 52 in Figs. 2 and 5, and the face of the guide-plate is slotted vertically, as shown at 53, these slots registering with the slots 39 of the 115 knife-block. Each slot in the guide-plate is thicker than a match-splint by the thickness of the knife 37, so that when the knife descends and severs a series of splints it will cause them to just fill the slots 53, and the 120 knife will hold them there until the descending comb 54 engages them and pushes them downward into the sticking-plate 56 beneath. A comb 54 has its teeth adapted to enter the 125 slots 53 of the guide-plate, and each tooth is thickened and inclined at the top, as shown at 55, so as to fit into the inclined space 52 of the guide-plate.

It is obvious that the cutting and ejecting mechanism described can be made to deliver 130 splints in many usual forms of carrier; but I prefer to use an ordinary plain plate 56, which is perforated, as shown in Fig. 4, to receive the ends of the splints, and the perfor-

lations are adapted to register with the slots 53 of the guide-plate. As presently described, it will be seen that a whole series of these plates 56 are fed through the machine, the plates running on a supporting-way 56^a, and the plates are not shown hinged together; but it will be understood that, if desired, they may be connected together as they pass through the machine, so as to be brought into connection with any usual dipping attachment.

The means for feeding the plates is as follows: Each plate 56 has on opposite sides ratchet-teeth 56^b, which are engaged by the pawls 57, and the latter are moved back and forth by the slide-plates 50, to which they are attached and which have already been referred to. The slide-plates 50 are each attached to a slide 58, (see Fig. 3,) which moves back and forth in a slideway formed between rails or plates 59, these being adjustable on the inner side of the frame 11, as the drawings show. On the shaft 20, near opposite sides of the machine, are cam-disks 60, having cam-grooves, as shown by dotted lines, which receive pins or rollers 61 of the customary kind on the slide bars or plates 58. It will be seen, then, that at every revolution of the shaft 20 the slide-bars 58 and slide-plates 50 will be moved backward and forward, and this causes the pawls 57 to engage the teeth 56^b and push the sticking-plate 56 ahead at each stroke of the slide-plate 50. It is obvious that many forms of ratchet-feed can be substituted for that described without affecting the principle of the invention.

The plates 56 are of a size to be conveniently handled, so that, if desired, the splints which they carry may be dipped by hand, and for this reason, as several plates 56 are contained in the machine at one time, (see Fig. 2,) I provide means for feeding the first plate as well as the second. To this end the second set of slide-plates 50^a (see Fig. 2) are arranged near the front of the machine, and these are provided with pawls 57^a to engage the ratchet-teeth 56^b. The slide-plates 50^a are connected to the slide-plates 50 by tie-rods 65, so that the two sets of slide-plates may reciprocate in unison.

To prevent any possible backward movement of the sticking-plate 56, ordinary detents 62 are used to engage the ratchet-teeth 56^b, these being pivoted on arms 63 and pressed into engagement with the ratchet-teeth by springs 64.

The operation of the machine is as follows: A series of veneer strips are placed between ribs 43 of the feed-table 52, being held, as described, with their edges uppermost and in parallel relation. These strips are fed forward by the feed-rollers 44 and 45 through the slots 39 of the knife-block 38 41. The ratchet-feed described causes the strips to pass into the slots 53 of the guide-plate 51 just the thickness of a match-splint, and they

are at this moment beneath the reciprocating knife 37. As the knife descends it simultaneously severs the splints from the ends of the veneer strips and forces the severed splints 70 into the slots 53, just filling the slots. During the descent of the knife 37 the ejecting-comb 54 is at rest; but as the knife starts on the up-stroke the comb 54, actuated by the cam-and-lever mechanism described, makes a quick 75 stroke down and up and strikes the splints while they are still in engagement with the knife 37, the knife serving as a guide or wall until the splints are driven below the slots 39. The comb 54 drives the splints downward into the holes of the sticking-plate 56, which register with the slots 53, above referred to. When the comb has ascended and as the knife 37 again descends, the slide-plates 50 are moved and advance the sticking-plate 85 56, so as to bring another set of holes beneath the slot 53.

I wish it distinctly understood that the carrier, which in this case comprises the plate 56, is not claimed as a part of this invention. 90 I prefer, however, to use a plate form of carrier because the plate can be held so rigid in the machine, and for this reason the holes in the plate are practically certain to register with the slots 53 of the guide-plate, as already 95 remarked. It will be clearly understood that these plates may be connected together in any mechanical way so as to make a continuous carrier, if desired, and the customary process for dipping may be used in connection with 100 it. It will be noticed, therefore, from the above description that my invention relates chiefly to the cutting and sticking mechanism, that this is very simple, that the strips of veneer are held so as to cut from edge to edge, which 105 is, I believe, a novelty in multiple cutting, and, further, that the splints are cut by a single knife, which serves as a guide, which prevents their displacement until they are driven into a carrier. 110

Having thus described my invention, what I claim as new, and desire to secure by Letters Patent, is—

1. A match-machine comprising guide mechanism adapted to hold a plurality of veneer strips in parallel relation, a reciprocating knife arranged to strike the edges of the veneer strips and cut them from edge to edge, a slotted guide-plate to receive the splints severed from the ends of the veneer strips, 120 and means for ejecting the severed splints from the guide-plate during the back stroke of the knife. 115

2. A match-machine comprising a horizontal feed-table having guiding mechanism for holding a series of veneer strips, edge up, and in parallel relation; a vertically-reciprocating knife, arranged to cut the veneer strips from edge to edge; a vertically-slotted guide-plate behind the path of the knife, feed mechanism to move the veneer strips the thickness of a match-splint beneath the knife, and 130

an ejecting mechanism to force the splints from the guide-plate.

3. A match-machine comprising a horizontally-moving carrier, guiding mechanism above the carrier adapted to hold a series of veneer strips, edge up, and in parallel relation; a feed mechanism to advance the veneer strips step by step the thickness of a match-splint at each step, a vertically-reciprocating knife to sever splints from the ends of the veneer strips, a vertically-slotted guide-plate behind the knife to receive the severed splints, and an ejecting-comb operating during the upstroke of the knife to force the splints from the guide-plate into the carrier.

4. A match-machine comprising a knife-block having parallel slots therein adapted to receive veneer strips and hold them in parallel relation, a single knife sliding over 20 the face of the knife-block and adapted to cut the veneer strips from edge to edge, a guide-plate opposite the knife-block, said plate having slots to receive the severed splints, and an ejecting device to force the splints from the guide-plate.

5. A match-machine comprising a vertically-slotted knife-block adapted to receive a series of veneer strips and hold them in parallel relation, a single knife moving across 30 the face of the knife-block adapted to sever the ends of the veneer strips which protrude from the knife-block, a slotted guide-plate behind the knife-block, the slots being adapted to receive the splints severed from the ends of the veneer strips, and an ejecting-comb arranged to move into the guide-plate

and eject the splints while the latter are still held by the knife.

6. A match-machine comprising a horizontally-movable carrier, a knife-block located 40 above the carrier and provided with a series of parallel vertical slots, a feed mechanism for feeding veneer strips through the slots of the knife-block, step by step, the thickness of a splint at each step, a single knife reciprocating across the face of the knife-block so as to simultaneously sever the protruding ends of the veneer strips thus forming splints, a guide-plate opposite the knife-block, said guide-plate having vertical slots to receive 50 the severed splints, and an ejecting-comb moving while the knife still engages the splints, to push the splints from the guide-plate into the carrier.

7. A match-machine comprising a horizontal feed-table having guide mechanism to hold a series of veneer strips, edge up, and in parallel relation; a slotted knife-block at the end of the table, the slots of the knife-block being adapted to receive the veneer strips, 60 a single knife sliding across the face of the knife-block to sever a whole series of veneer strips, a vertically-slotted guide-plate behind the path of the knife to receive the severed splints, and an ejecting-comb moving through 65 the slots of the guide-plate to drive the splints into the carrier substantially as described.
